UNITED STATES PATENT OFFICE.

OLIVER D. WOODRUFF, OF SOUTHBURG, CONNECTICUT.

CAR-COUPING TOOL.

SPECIFICATION forming part of Letters Patent No. 410,061, dated August 27, 1889.

Application filed July 16, 1889. Serial No. 317,683. (No model.)

To all whom it may concern:

Be it known that I, OLIVER D. WOODRUFF, a citizen of the United States, residing at Southbury, in the county of Hartford and State of Connecticut, have invented certain new and useful Improvements in Car-Coupling Tools, of which the following is a specification.

My invention relates to improvements in car-coupling tools of the class which are designed for use in lifting and guiding the coupling-link into place, and the chief objects of my improvement are to increase the efficiency and convenience of the tool and to simplify its construction.

In the accompanying drawings, Figure 1 is a side elevation of my coupling-tool, together with a sectional view of the coupling-link, and Fig. 2 is a plan view of said tool with a portion of the coupling-link indicated by broken lines.

I form the main portion of the tool of a simple rod bent into shape to form two seats *a a* for the two sides of the coupling-link, and an intermediate upwardly-projecting guide *b*. I form this guide by bending the rod upon itself, so that it curves gradually upward from each of the seats *a*. I prefer to form a slight upward deflection *c* on the inner or handle side of the intermediate guide, also to bend the outer end *d* of the rod upwardly from the outer one of the seats *a a*, as shown; but these are not essential to the main features of my invention. I provide the long end of the rod with a handle *f*, of wood or other proper material.

In use the tool is designed to be held substantially horizontal, as shown in Fig. 1, with the guide *b* inside of the link *g*, while the two sides of the link rest upon the two seats *a a*. The operator can, when the link is thus resting upon the tool, guide it so that it will properly enter the coupling, and by reason of both sides of the link resting upon the seats

a a the link may be prevented from twisting out of a parallel position to the opening in the coupling. The guide *b* will not only assist in guiding the link laterally, but it will effectually prevent the link from slipping endwise off the tool.

The tool may be used by hooking it upon one side of the link only and permitting the outer end to go inside the link; but this might not always be effective in case the link was inclined to twist. In such a case it should be supported upon both sides by the seats *a a* and guided by the guide *b* on the inside of the link. In case the tool is caught or struck violently between the couplings, the handle *f* will receive the jar, so as to prevent the vibration of the tool from stinging the hand of the operator.

I claim as my invention—

1. The herein-described car-coupling tool, consisting, essentially, of a proper handle and body having two seats *a a*, for supporting the opposite sides of the link, and an intermediate upwardly-projecting guide *b*, substantially as described, and for the purpose specified.

2. The herein-described car-coupling tool, consisting of a rod having the return-bend to form the upwardly-projecting guide *b*, and having also two seats *a a* on the opposite sides of said guide for supporting the opposite sides of the link, substantially as described, and for the purpose specified.

3. The herein-described car-coupling tool, consisting of the rod having the two seats *a a* for supporting the opposite sides of the link, an intermediate upwardly-projecting guide *b*, and outer end *d*, bent upwardly from the outer one of the seats *a a*, substantially as described, and for the purpose specified.

OLIVER D. WOODRUFF.
